WIRE BENDING MACHINE

John C. Lincoln, Scottsdale, Ariz., and Svend G. Blumensaat, Beachwood Village, Ohio, assignors to The Universal Wire Spring Company, Bedford, Ohio, a corporation of Ohio

Application September 24, 1953, Serial No. 382,028

16 Claims. (Cl. 140—71)

This invention relates to wire bending machines producing zigzag bent or sinuously corrugated wire strips such as used for making wire springs for seat and back spring structures, cushions and the like and, more particularly, to a wire bending machine in which pivotally mounted wire bending arms cooperate with vertically and horizontally shiftable wire forming and transferring elements in alternately engaging and bending a wire in opposite directions as the wire passes between the wire bending arms of the machine. This type of wire bending machines has its wire bending arms pivoted to swing in a horizontal plane and its wire forming and transferring elements arranged to oscillate in planes angularly related to said horizontal plane to effect engagement and disengagement with newly formed loops of the wire strip for step by step advancement of the strip through the machine and makes it difficult to adjust the machine for wires differentiating in physical properties, particularly, as such wire bending machines during this type of rather common adjustments should be kept running to avoid excessive production losses.

The general object of the present invention is the provision of an improved wire bending machine of the general type referred to above, in which the pivotally mounted wire bending arms are arranged to oscillate in spaced, parallel planes, in which the forming and transferring elements cooperating with the wire bending arms are pivotally mounted to oscillate and reciprocate in such spaced, parallel planes to properly form loops in the wire to be bent and in which the wire and formed wire strip are vertically reciprocated by stripper-like shifting means and alternately shifted from one of said planes into the other one to effect disengagement of the wire and formed wire strip from one wire bending arm and its cooperating forming and transferring element and engagement of the formed wire strip with the other forming and transferring element for progressively advancing the formed wire strip through the machine and successive bending of the wire by the other bending arm in cooperation with said other forming and transferring element.

Another object of the invention is the provision of an improved wire bending machine of the general type referred to above, in which pivotally mounted wire bending arms and pivotally mounted reciprocating forming and transferring elements provided with forming and wire transfer means have such forming and transfer means arranged to oscillate in two vertically spaced, parallel planes for cooperative bending of a wire in either one of said planes, and in which stripper-like shifting means are arranged to be oscillated in vertical planes or planes perpendicular to said parallel planes to alternately transfer the wire and formed wire strip from the wire forming means in one plane to the wire forming and transfer means in the other plane.

A further object of the invention is the provision of an improved wire bending machine of the type referred to above which embodies readily accessible adjusting means adapted to permit effective individual and joint adjustment

2

of working parts of the machine when running for full control of shape, form and spacing of the loops of zigzag or sinuously corrugated wire strips produced by such wire bending machine.

5 Still another important object of the invention is the provision of a wire bending machine constructed to rapidly, accurately and inexpensively shape a wire to a zigzag or sinuously corrugated wire strip, the wire bending machine being of as simple a design and low cost as possible and practical and efficient for all purposes intended.

Additional objects and novel features of construction, combinations and relations of parts by which the objects in view have been attained will appear and are set forth in detail in the course of the following specification.

The drawings accompanying and forming part of the specification illustrate a certain practical embodiment of the invention, but it will be apparent as the specification proceeds that the structure may be modified and changed in various ways without departure from the true spirit and broad scope of the invention.

In the drawings:

Fig. 1 is a plan view partly in section of a wire bending machine constructed in accordance with the invention; the view being taken on line 1—1 of Fig. 9;

Fig. 38 is a front view of Fig. 37; and

Fig. 39 is an end view of Fig. 38.

Referring now more in detail to the exemplified form of the invention shown in the drawings, the wire bending machine shown therein embodies a housing 2 mounting in roller bearings 3 and 4 a main drive shaft 5 which is driven by a motor 6 coupled therewith by releasable clutch means 7 and a Reeves drive pulley arrangement 8. Main drive shaft 5 is geared to a cam and drive shaft 9 by reducing gearing 10 including a drive pinion 11 on drive shaft 5 and a large gear 12 on cam and drive shaft 9, the latter shaft being journaled in ball bearings 14, 15 and 16. Cam drive shaft 9 is coupled with a rotary speed meter 184 and actuates a wire bending mechanism 17 arranged on the top of housing 2, as will be described hereinafter. Wire bending mechanism 17, which is designed to shape a straight wire into a zigzag bent or sinusously corrugated wire strip, receives for such purpose wire 18 from a source of supply (not shown), and this

wire is straightened by passing through a wire straightener 19 of standard design (see Fig. 1) embodying parallel pairs of rollers 20 arranged in somewhat staggered relation with respect to each other and a pair of rollers 21 arranged at a right angle to the pairs of rollers 20, all individual and pairs of rollers being adjustably supported. Actuation of wire bending mechanism 17 is effected by cam and drive shaft 9 which for such purpose mounts two symmetrically arranged bevel gears 22, 23 meshing with similar bevel gears 24, 25 on two symmetrically arranged vertical shafts 26, 27 and effects rotation of these shafts in opposite direction with respect to each other, as indicated by arrows 28, 29 in Figs. 6 and 10. Vertical shafts 26 and 27 are journaled in bearings 30 and 31 and rigidly support eccentrics 32, 33 which effect reciprocatory movements of transfer arm links 34, 35 by engagement of sleeve-like end portions 36, 37 of said transfer arm links with eccentrics 32, 33 and thus change the circular motion of shafts 26 and 27 to a reciprocatory motion of the transfer arm links for a purpose later to be described. Eccentrics 32, 33 furthermore mount in laterally offset relation with respect to vertical shafts 26 and 27 stud shafts 38, 39 which pivotally support by means of bearings 40 the one ends 41 of bending arm links 43 for a purpose later to be described. Eccentrics 32, 33 are rotated in opposite directions with respect to each other and transfer their rotary motion to wire bending arm 45, 46 mounted on vertical shafts 47, 48 and wire forming and transfer arms 49, 50 mounted on other vertical shafts 51, 52. The vertical shafts 47, 48 which are freely rotatably mounted in bearings 54 on top plate 53 of housing 2 support on their lower shaft portions 55, 56 crank arm levers 57 which have their one ends 59 splined to said lower shaft portions and their perforated other ends 61 pivoted by pins 63 to the bifurcated ends 64 of bending arm links 43 to convert the rotary movement of shafts 26, 27 to oscillatory movements of vertical shafts 47, 48 and wire bending arms 45, 46 mounted on said shafts. Vertical shafts 51, 52 are also freely rotatably mounted on top plate 53 by means of bearing 66 and these shafts support on their lower shaft portions 67 adjustable crank arm levers 69, 70 splined with their one ends 71 to shaft portions 67. Crank arm levers 69, 70 adjustably support pivot pins 73 which pivotally connect these crank arm levers with the bifurcated other ends 74, 75 of transfer arm links 34, 35 to convert the rotary movement of shafts 26, 27 and eccentrics 32, 33 into oscillatory movements of vertical shafts 51, 52 and wire forming and transfer arms 49, 50 mounted thereon. Pivot pins 73, as shown in Figs. 10 through 12, are mounted in blocks 76 which are shiftably arranged in elongated slots 77 of crank arm levers 69, 70 and positively shifted in said slots by screw members 78 swiveled in crank arm levers 69, 70 and threadedly engaged with threaded bores 79 in blocks 76. To effect in wire bending operations progressive shifting of the formed wire strip through the wire bending machine, wire bending arms 45, 46 and cooperating wire forming and transfer arms 49, 50 are oscillated in parallel, vertically spaced planes, one wire bending arm and its cooperating wire forming and transfer arm being oscillated in one plane and the other wire bending arm and its cooperating wire forming and transfer arm being oscillated in the other plane; wire 18 and the wire strip formed therefrom are alternately shafted from one of these planes into the other one and vice versa. Furthermore, after each shifting wire 18 and the formed wire strip are advanced through the wire bending machine in step-by-step motion alternately by wire forming and transfer arms 49, 50 and after each advance motion wire 18 is again subjected to bending operations by cooperative action of the respective wire bending arms 45, 46 and wire forming and transfer arms 49, 50.

The alternate shifting of wire 18 and the formed wire

strip from one plane into the other and vice versa is effected by a stripper mechanism which embodies a stripper assembly 80 and a stripper shifting arrangement 81 actuated in timed relation with respect to the oscillations of wire bending arms 45, 46 and wire forming and transfer arms 49, 50, as will be later described.

Stripper assembly 80 embodies two similarly constructed stripper units 82, 83 adjustably supported in inverted position with respect to each other on two parallelly arranged, elongated shafts 84, 85. Each of these stripper units embodies a stripper bracket 86 of substantially T-shaped cross section, the base or flange portion 87 of which includes bores 88, 89 for shafts 84, 85 and the middle portion 90 of which is slotted to form an elongated channel 91. Each of the thus constructed stripper brackets 86 has attached to its middle portion 90 a plurality of vertically arranged stripper blades 92 which differentiate in length to fit the shape of the loops formed in the wire and are attached to slotted middle portion 90 by bolts 95. Preferably, as shown (see Fig. 30), each channel 91 at its rear portion 96 is covered by a hardened steel plate 97 which is attached to stripper bracket 86 by machine screws 98.

The two stripper units 82, 83 which are adjustably supported on elongated shafts 84, 85, are in their adjusted positions rigidly held on said shafts by nut members 99 and are spaced from each other by two adjustable assemblies 100 of perforated spacing blocks 101, 102, which assemblies have their spacing blocks sleeved upon shafts 84, 85 in inverted position with respect to each other and which have such spacing blocks non-rotatably engaged with said shafts by key members 103. The two spacing blocks 101 and 102 of each adjustable assembly are each formed with threaded end portions 104, 105, respectively, which in inverted positions of such spacing blocks extend toward each other and are formed with right-handed and left-handed threads respectively. The thus constructed spacing blocks 101 and 102 are coupled with each other by an adjusting nut member 106 formed at its one end portion 107 with right-handed threads and at its other end portion 108 with left-handed threads to effect by rotation of nut member 106 a change in the spacing of the two stripper units 82, 83.

Vertical shifting of stripper assembly 80 in opposite directions is effected by cam and drive shaft 9 geared to vertical drive shafts 26, 27 of wire bending mechanism 17. For such purpose cam and drive shaft 9 rigidly mounts midway between its opposite ends a cam assembly 109 of the stripper shifting arrangement 81, which cam assembly rotates with cam and drive shaft 9 and effects oscillation of lever member 110 pivoted at its one end 111 to bracket 112 on housing 2 and at its other end 114 slidably coupled with downwardly extended ear portions 115 of cross bar member 116, the perforated end portions 117 of which are sleeved upon and secured to lower end portions 118, 119 of elongated shafts 84, 85 of the stripper assembly. Cam assembly 109 embodies two parallelly arranged cam disk members 120, 121 which are rotatably adjustably mounted on a base member 109' keyed to cam and drive shaft 9 and actuate upon cam rollers 122, 123 mounted on lever member 110 and bracket 124 of such lever member in a fashion to positively oscillate lever member 110 and the stripper assembly coupled therewith.

The wire bending arms 45 and 46 (Figs. 34 through 36) which cooperate with wire forming and transfer arms 49 and 50 (Figs. 37 through 39) each embody a hub portion 125 splined to the respective shaft 47, 48 and a perforated end portion 126 mounting in its perforation a forming button 127, and the wire forming and transfer arms 49 and 50 each embody a hub portion 128 splined to the respective shaft 51, 52 and a perforated end portion 129 mounting a forming button 130 and a wire retaining block 131. Cooperation of wire bending arm 45 with wire forming and transfer arm 49, and wire bend-

ing arm 46 with wire forming and transfer arm 50 will be understood from diagrammatic views 23, 24 and diagrammatic views 25, 26.

The wire forming and transfer arms are coupled with a wire and wire strip control unit 132 fastened to top plate 53 of housing 2 by pin 182 and screw member 183. Wire strip control unit 132 effects step-by-step advancement of the wire strip through the wire bending machine, controls the shape and spacing of the loops of the formed wire strip and provides the necessary adjustments for the desired control of bending operations.

This wire strip control unit, which can readily be adjusted during operation of the wire bending machine, embodies two spaced supporting brackets 133, 134 which are secured to top plate 53 of the machine, two superposed supporting blocks 135, 136 arranged between said brackets and connected therewith by bolts 137, and two transfer block members 138, 139 formed with transfer head portions 140, 141 and transfer shaft portions 142, 143 respectively, which transfer portions are slidably and non-rotatably guided in bores 144, 145 of supporting blocks 135, 136. Control unit 132 is positioned to locate transfer head portions 140, 141 of transfer block members 138, 139 with respect to predetermined positions of forming buttons 127 of wire bending arms 45, 46 and forming buttons 130 of wire forming and transfer arms 49, 50 to effect by alternate engagement of cross members 148 of the formed wire strip with extended portions 146, 147 on transfer head portions 140, 141 step-by-step advancement of such wire strip when shifted by stripper assembly 80 into either one of the two planes in which forming buttons 130 of the forming and transfer arms 49, 50 are oscillated and in which transfer block members 138, 139 are reciprocated by their yielding coupling with the forming and transfer arms, as will be presently described.

Transfer block members 138, 139 have their head portions 140, 141 yieldingly shiftably coupled with the perforated end portions 129 of the wire forming and transfer arms 49, 50 by headed screws 149 which are freely shiftably extended through slots 150 in end portions 129 of forming and transfer arms 49, 50 and adjustably extended into threaded bores 151 in slotted ends 152 of head portions 140, 141 and rigidly held in adjusted positions by clamping screws 153 in the slotted ends 152. This yielding, shiftable coupling of transfer block members 138, 139 with wire forming and transfer arms 49, 50, which includes compression springs 113 arranged between block members 138, 139 and forming and transfer arms 49, 50, permits limited lost motion between the transfer block members and wire forming and transfer arms, which lost motion is utilized to control the amplitude of the reciprocatory movements of the transfer block members in bores 144, 145 and therewith control the shape and form of the finished wire strip. Such a control is effected by arranging in bores 144, 145 stop members 154, 155 which embody right-handed and left-handed screw portions 156, 157, respectively, adjustably threadedly engaged with split adjusting screw retainers 158, 159 attached to supporting blocks 135, 136 by machine screws 160. Split adjusting screw retainers 158, 159 securely and non-rotatably grip screw members 156, 157 when knobbed clamping screws 161, 162 are screwed home to be forced against the screw retainers 158, 159 (see Fig. 19).

Axial adjustment of screw members 156, 157 in bores 144, 145 is effected by rotation of these screw members after release of knobbed clamping screws 161, 162 by worm gear drives 163, 164. For such purpose screw members 156, 157 have slidably keyed thereto worm gears 165, 166 engaged with worm shafts 167, 168, respectively, journaled in and extended through bearing sleeves 169 which are extended through bores 170 in right-hand supporting bracket 133 into bores 171 in supporting blocks 135, 136. Each of the worm shafts 167,

168 supports on its reduced outer end 172 a flanged thimble 173 pinned thereto, which thimble supports a spur gear 174 forced into frictional contact with the flange 175 of the thimble by a jam nut 176 threadedly engaged with the threaded ends 177 of the thimble. Joint rotation of worm shafts 167, 168 and screw portions 156, 157 of stop members 154, 155 driven thereby in opposite directions with respect to each other to simultaneously shift the stop members in the same direction is effected by a master spur gear 178 which meshes with the two spur gears 174 and is freely rotatably journaled on a stud shaft 179 mounted on right-hand supporting bracket 133 in symmetrical relation with respect to worm shafts 167, 168. Master spur gear 178 has rigidly attached thereto a dial 180 and mounts a handle 181 for manual rotation of such master spur gear.

Individual adjustment of either one of stop members 154, 155 is readily effected by loosening the respective one of the clamping screws 161, 162 and the respective jam nut 176 to permit free rotation of one of the two stop members by actuation of the respective worm gear drive and rigidly hold the other one of such stop members against rotation by the respective split adjusting screw retainer, such loosening up of the respective jam nut 176 permitting free rotation of the respective spur gear 174 on its thimble 173.

Outlining the operation of the wire bending machine, it will be understood by reference to the drawings that each revolution of cam and drive shaft 9 causes, by co-operation of bending arms 45, 46 with the respective wire forming and transfer arms 49, 50 formation of left and right-handed loops in wire 18; that after each individual left or right-hand bending operation the wire with the formed wire loop is vertically shifted by stripper assembly 80 to transfer the wire loop from the forming button of a wire forming arm to the forming button of a transfer block member coupled with the respective wire forming and transfer arm; that each transfer block member after receiving a loop on its forming button advances same on the forward stroke of the respective transfer block member and that after stripping the wire loop from the forming button of such transfer block member the transfer and forming arm with the transfer block member is retarded to starting position ready to effect in co-operation with the respective wire bending arm further wire loop bending operations.

Form and shape of the wire loops formed by the described wire bending and forming operations is partly controlled by wire forming buttons 127, wire retaining blocks 131, and the oscillatory movements of wire bending arms 45, 46 and wire forming and transfer arms 49, 59. The oscillatory movements of wire forming and transfer arms are controlled by the active length of crank arm levers 69, 70 which, when adjusted, effect an increase or decrease in the stroke of wire forming and transfer arms 49, 50. Furthermore, form and shape of the wire loops and their spacing is controlled by the reciprocatory movements of transfer block members 133, 139 of control unit 132, which transfer block members are yieldingly coupled with corresponding forming and transfer arms to permit a change in the length of the stroke of the reciprocatory movement of transfer block members 138, 139 without changing the stroke of the oscillatory movement of forming and transfer arms 49, 50 by stop members 138, 139 of control unit 132, an arrangement which permits a change in the form of the loops and their spacing. Changing of the form of the loops and their spacing, which may be exercised while the wire bending machine is operating, is possible after release of clamping screws 161, 162 and is effected by rotation of master spur gear 178 by handle 181. Thus a rotation of master spur gear 178 effects by worm gear drives 163, 164 joint shifting of stop members 154, 155 in one or the other direction and thereby changes the

stroke of the reciprocatory movements of transfer block members 138, 139.

Control unit 132, in addition to control of shape and form of all the loops, also permits a change in the shape of all right-hand or left-hand loops by increasing or decreasing the stroke of the reciprocatory movements of stop member 154 with respect to stop member 155 or vice versa. Such individual control of the stop members 154 and 155 which also may be exercised while the machine is operating is possible after release of the respective one of the two clamping screws 161, 162 and the respective jam nut 176 by rotation of master spur gear 178 to shift the respective stop member in the desired direction while securely holding the other stop member against shifting by the respective one of the clamping screws 161, 162.

Having thus described our invention, what we claim is:

1. In a wire bending machine a pair of cooperating wire bending and forming means arranged to oscillate in a plane to bend a wire in one direction and form open loops therein, a second pair of cooperating wire bending and forming means arranged to oscillate in another plane to bend such wire in the opposite direction and form open loops therein, said latter plane being spaced from said first plane and parallel thereto, reciprocatory stripping means arranged to reciprocate in a plane perpendicularly related to said other two planes adapted to effect transferring of open wire loops formed by the wire bending and forming means in one plane to the wire forming and bending means in the other plane, actuating means for said pairs of cooperating wire bending and forming means, and actuating means for said stripping means controlled by said first actuating means and adapted to effect vertical reciprocatory shifting of said stripping means when said pairs of wire bending and forming means are in predetermined positions with respect to each other.

2. A wire bending machine as described in claim 1, wherein the cooperating wire bending and forming means of each pair of wire bending and forming means are oscillated in substantially opposite directions toward and away from each other.

3. A wire bending machine as described in claim 1, wherein corresponding wire bending and forming means of said pairs of cooperating wire bending and forming means when oscillated overlap each other at the end of each wire bending movement to permit the stripping means to strip open wire loops formed by bending and forming means oscillating in one plane and transfer such open wire loops onto wire bending and forming means oscillating in the other plane.

4. A wire bending machine as described in claim 1, wherein the actuating means for said pairs of cooperating wire bending and forming means includes a drive shaft, a pair of symmetrically arranged eccentrics geared to said drive shaft and coupled with one of the bending and forming means of each pair thereof, and crank means mounted on each of said eccentrics and coupled with the other one of the bending and forming means of each pair thereof, and wherein the actuating means for said stripping means include pivotally supported lever means coupled with said stripping means and cam means coupled with lever means and mounted on said drive shaft to effect shifting of said stripper means in timed relation with respect to the movements of said pairs of cooperating wire bending and forming means.

5. A wire bending machine as described in claim 1, wherein one of the wire bending and forming means of each pair thereof consists of a bell crank-like lever arrangement having a wire bending and forming arm and a longitudinally adjustable connecting arm, and wherein the actuating means for said pairs of cooperating wire bending means include eccentrics coupled with the longitudinally adjustable connecting arms of said bell crank-like lever arrangement to control their rotary oscillations,

said connecting arms being longitudinally adjustable to change their active length.

6. A wire bending machine as described in claim 1, wherein the stripping means include a pair of axially spaced, aligned stripper units arranged in inverted position with respect to each other and wherein these stripper units are adjustably shiftably connected with each other to permit a change in their axial spacing.

7. A wire bending machine as described in claim 1, wherein the stripping means embody a pair of similarly constructed stripper units, coupling means adjustably connecting the stripper units with each other in axially spaced alignment and inverted position with respect to each other, and elongated, parallelly arranged supporting means for the thus connected stripper units.

8. A wire bending machine as described in claim 7, wherein the stripping units of said stripper means include at their opposing end portions stripping plates, and wherein such stripper plates are spaced from each other a distance larger than the gauge of the wire to be shaped in said wire bending machine.

9. In a wire bending machine a pair of cooperating wire bending and forming means arranged to oscillate in a plane to bend a wire in one direction and form opening loops therein, a second pair of cooperating wire bending and forming means arranged to oscillate in another plane to bend such wire in the opposite direction and form open loops therein, said latter plane being spaced from said first plane and parallel thereto, reciprocatory stripping means arranged to reciprocate in a plane perpendicularly related to said other two planes adapted to effect transfer of open wire loops formed by the wire bending and forming means in one plane to the wire bending and forming means in the other plane, and a longitudinally shiftable transfer block member for each pair of cooperating wire bending and forming means coupled with one cooperating wire bending and forming means thereof.

10. A wire bending machine as described in claim 9, wherein each shiftable transfer block member embodies a head portion slidably coupled with one of the cooperating bending and forming means of a pair of bending and forming means and a shaft portion yieldingly shiftably coupled with said one of the bending and forming means, a control-housing slidably supporting the shaft portions of said shiftable transfer block members and stop members adjustably mounted in said control-housing adapted to arrest movements of said shaft portions when shifted in a predetermined direction.

11. A wire bending machine as described in claim 10, wherein the shaft portion of each shiftable transfer block member is non-rotatably, slidably supported in the control-housing, wherein such shaft portion has its coupled end enlarged and shaped to form a transfer head for an open loop of the formed wire strip, and wherein such transfer head includes a shoulder portion adapted to engage a loop connecting cross member of the formed wire strip to effect in bending, forming and advancing operations a control of the spacing of the cross members of the formed wire strip.

12. A wire bending machine as described in claim 10, wherein the stop members in said control-housing are axially shiftably mounted therein, and clamping means

adapted to rigidly hold said stop members in their adjusted positions.

13. A wire bending machine as described in claim 12, wherein each stop member embodies a threaded portion threadedly engaged with split clamping nut means forming a wall portion of the control-housing, actuating means for said clamping nut means adapted to effect its clamping action on the threaded portion of the stop member, and worm gear drive means for said stop member including a worm gear slidably keyed thereto and adapted to effect rotation of the stop member for its axial movement in the control-housing when the clamping nut means are released.

14. A wire bending machine as described in claim 13, wherein each worm gear drive means for a stop member includes a worm shaft extended out of the housing, a gear on the extended portion of each worm shaft releasably coupled therewith and a master gear engaged with the gears on the said worm shafts for joint and individual actuation of the worm gear drive means by said master gear.

15. In a wire bending machine a pair of cooperating bell crank-like lever arrangements having cooperating wire bending and forming arms arranged to oscillate in a horizontal plane and operating arms, a second pair of cooperating bell crank-like lever arrangements having cooperating wire bending and forming arms arranged to oscillate in a horizontal plane spaced from said first plane and operating arms, stripping means arranged to reciprocate in a plane arranged at a right angle to said first two planes and adapted to directly transfer wire loops formed by one pair of cooperating wire bending and forming arms to wire bending and forming arms of the other pair thereof, eccentrically driven sleeve link means coupled with the operating arm of one of the bell crank-like lever arrangements of each pair thereof and crank means coupled with the operating arm of the other one of the bell crank-like lever arrangements of each pair thereof.

16. A wire bending machine as described in claim 15, wherein one bell crank-like lever arrangement of each pair thereof shiftably supports on its operating arm a coupling member arranged to be adjustably shifted lengthwise thereof, and wherein such coupling member is pivotally connected to the eccentrically driven sleeve member to change the stroke of the rotary oscillations of such bell crank-like lever arrangement when the coupling member is adjustably shifted on the operating arm to adjust its active length.
